UNITED STATES PATENT OFFICE.

GEORGE P. LELY, OF PARKSTONE HEIGHTS, ENGLAND.

DATE-INDICATOR.

1,381,881.

Specification of Letters Patent. Patented June 14, 1921.

Application filed April 29, 1919. Serial No. 293,475.

To all whom it may concern:

Be it known that I, GEORGE PEEL LELY, a subject of His Majesty the King of Great Britain, and resident of Parkstone Heights, 5 in the county of Dorset, Kingdom of England, have invented certain new and useful Improvements in or Relating to Date-Indicators, of which the following is a specification.

10 This invention relates to a device for use as a date indicator, perpetual date indicator and like device and has for its object to provide an improved construction of device adapted for use as a date indicator wherein 15 the day of the week and the day of the month are positively and correctly indicated so that no confusion or dubiety can arise as to whether say the seventh of any particular month is a Sunday, Monday, Friday or other 20 day of the week.

According to this invention the device broadly comprises two pointers relatively adjustable and simultaneously movable rectilinearly, or circularly over, around or adjacent 25 a numerical scale and a diurnal scale, so that the two pointers or index fingers can be set at the beginning of a month, one to the day of the month and the other to the day of the week, the two pointers or index 30 fingers hereinafter referred to as pointers, being thereafter simultaneously movable by hand or mechanically by gear to indicate the day of the week and the day of the month positively and correctly throughout 35 the entire month.

A device in accordance with the present invention may be constructed in the form of a rectangular tablet or flat or circular board or may be applied to a Geneva or 40 other watch or to a clock.

I will describe with reference to the accompanying drawings constructions in accordance with the present invention, but I do not limit myself to the precise constructions hereinafter described and illustrated.

Figure 1 is an elevation of a date indicator in accordance with the present invention.

Fig. 2 is a central vertical section on the 50 line *a*—*b* Fig. 1 and Fig. 3 is a cross section on the line *c*—*d* Fig. 1.

Fig. 4 is an elevation of a modified form of date indicator also in accordance with the present invention.

55 Figs. 5, 6, 7, 8, 9 and 10 show views of

various constructions for carrying the adjustable pointers or index fingers.

Figs. 11, 12 and 13, show modified forms of pointer carrying member and Figs. 14 and 15 show a construction of pointer 60 formed as a spring clip.

Figs. 16, 17, 18 and 19 are respectively an elevation, a section on the line *e*—*f* Fig. 16 an elevation, and a section on the line *g*—*h* Fig. 18 of a modified form of date indicator 65 in accordance with the present invention.

Figs. 20, 21 show in elevation and section a further modified form of date indicator and Figs. 22 to 27 inclusive show still further modifications of the date indicator 70 hereinafter fully described.

Fig. 28 shows a table for use with date indicators according to the present invention, which table may be stamped, pasted or otherwise indicated on any of the constructions hereinafter described.

Figs. 29, 30 and 31 are respectively a side view of the clock actuated mechanism by which the pointers 9 and 10 shown in Fig. 23 are simultaneously moved once every 80 twenty four hours.

Referring to Figs. 1, 2 and 3 the device in its simplest form viz., the tablet form, comprises a rectangular board 1 of suitable thickness, flat on its upper face 2 and provided with a numerical scale 3 say on the left hand side of the board. This scale bears the numbers one to thirty one corresponding to the maximum number of days in a month. On the right hand side of the board is suitably indicated a diurnal scale 4 or the days of the week the first and last indications being preferably Sunday as at 5 and Tuesday as at 6 respectively. In front of or above the Sunday indication on the diurnal scale 90 4 are three additional indications viz.:—

Thursday, Friday and Saturday reading downwardly in the order of occurrence, and below the Tuesday indication at the bottom of the diurnal scale may be three additional 100 indications namely Wednesday, Thursday and Friday.

Between the two scales and movable in a suitable recess 7 in the tablet is a flexible member such as a thong 8 or other suitable 105 member carrying two pointers 9, 10 which are relatively adjustable so that either or both of the said pointers 9, 10 can be adjusted at the beginning of each month if found necessary, one to the number one on 110

the left hand side scale 3 or numerical scale on the tablet or board and the other to the correct day of the week on the diurnal scale 4 on the right hand side of the tablet. 5 Thereafter the two pointers 9, 10 may be moved simultaneously when desired to give the correct day of the month and day of the week by pulling or pushing the flexible thong 8 or other suitable member carrying 10 the pointers which in this construction point in opposite directions. The aforesaid movement would probably be effected daily. For example, assuming the 1st day of the month to be on a Wednesday the left hand pointer 9 or the thong or both pointer 9 and thong 15 is or are adjusted so that the pointer 9 comes opposite the numeral 1 on the left hand scale 3, and the right hand pointer 10 is adjusted to indicate Wednesday on the 20 diurnal scale 4. The two pointers 9, 10 are thus set and remain in this set position throughout the particular month for which they are set. On the morning of the second day of the month, the flexible thong 8 or 25 other member carrying the pointers 9, 10 is pulled or pushed into such position that the left hand pointer indicates the numeral 2 when it will be found that the right hand pointer then indicates Thursday, thus positively and correctly indicating that Thursday 30 is the second day of the month. The relative adjustment of the pointers may be effected through six or seven divisions of the diurnal scale to allow for the first day 35 of the month falling on any day of the week. Half of these divisions may be indicated as additional divisions at the beginning and end of the diurnal scale, or three of such divisions may be at the end and four at the 40 beginning as found most convenient thereby resulting in a reduction of the distance through which the relative adjustment of the pointers need be effected.

In Fig. 4 the thong 8 of Fig. 1 is shown 45 as being replaced by a screwed rod 11 held against translational movement by the milled nut 13. In this construction the pointers 9, 10 are formed as spring metal clips screwed internally so that on rotating 50 the screwed rod 11 the pointers can be simultaneously moved up and down as desired, the pointers being also removable bodily from the rod when desired. The construction shown in this figure is otherwise 55 the same as that of Fig. 1.

The adjustment of the pointers may be effected in any suitable and convenient manner, as for example by sliding one pointer say the pointer 10 in a slit 11 in the thong 60 8 relatively to the other pointer or by removing one pointer or both pointers bodily from the flexible thong or other carrying member and refixing the pointer or pointers in proper relation to the other; or if so desired sets of pointers bearing a fixed rela-

tion to each other may be employed, one set of which would probably fit one or more than one month, the other sets being used for the other months. Pointers of this nature are shown in Figs. 5 to 10 inclusive, these constructions showing two views viz. an elevation and plan of integral pointers. In Figs. 5 and 6 the pointers are shown as formed from a metal or other blank 13' having the pointers 9, 10 in alinement and 70 stamped up therefrom, the body of the blank being thereafter bent as at 14, 15 to form spring clips so that the pointers can be fastened or secured to the flexible thong or other carrying member. In Figs. 8 and 80 10 of which Figs. 7 and 9 are the respective elevations the pointers 9 and 10 and shown as being spaced apart, the distance apart of the pointers in Fig. 8 being equal to the distance between any two adjacent days and 85 in Fig. 10 the distance apart of the pointers corresponds to the distance between say Sunday and Tuesday. If so desired the pointers may be spaced apart any suitable distance as for example the pointer 9 may 90 be arranged to indicate the numeral 1 and the pointer 10 Wednesday in a downward direction or any day up to say Thursday in an upward direction. If so desired each set of pointers may have the month slidably 95 or otherwise suitably indicated thereon and the sets of pointers could be supplied yearly.

The member carrying the pointers may be solid as shown at 16 Fig. 11, which represents a rectangular piece of wood or metal 100 having the pointer 9 secured thereto and the pointer 10 formed of spring metal and slideable in a groove 17. Each end of the piece 16 is provided with a hook 18, 19 to which is attached a cord or wire as shown so that 105 the piece 16 and pointers 9, 10 can be moved simultaneously when desired. The piece 16 may be moved by hand in which case the hooks 18, 19 and corresponding cords or wires are unnecessary. If so desired the 110 member carrying the pointers 9, 10 may be hollow as shown at 20 Fig. 12 the pointer 9 being secured thereto and the pointer 10 being slideable in a slot 21 and made in the form of a spring clip. The member carrying the pointers may be round as shown at 115 11 Fig. 4 or square or hexagonal or of other suitable section and the pointers may be made from a metal blank 22 Figs. 14 and 15, the pointers 9, 10 being stamped or otherwise cut therein as shown and the body of the blank being subsequently bent round as at 22, to clip onto the carrying member.

When the leather thong is used as shown 125 in Fig. 1 the thong 8 may be suitably tensioned by passing the thong downwardly through holes 23, 24 arranged one at each end of the tablet and then upwardly through further holes 25, 26 adjacent the aforesaid holes. The thong 8 may have a loop or 130

equivalent at either end or at both ends for hanging purposes. A roller 28, Fig. 1, bearing the months or a number of slides having the months on one side and blank on the other side and capable of being inserted in position may be mounted in or on the upper end of the tablet. The roller 28 or the slides where used may be frictionally retained in place, the roller being rotated 10 when desired to indicate the proper month.

If so desired the pointers 9, 10 may be adjustable but otherwise immovable as shown in Figs. 16 and 18 and the numerical scale 3 and the diurnal scale 4 may be movable 15 instead of the pointers. These scales may be arranged one on each side of the pointer as shown in Fig. 16 or between the pointers as shown in Fig. 18. In each construction the scales are movable simultaneously to indicate the day of the week and month. The numerical and diurnal scales may be indicated on separate slides as 29, 30 Fig. 16 or on the same slide 31 as in Fig. 18 these slides being let into and slidable in 20 recesses or in a recess in the face of the tablet.

In an alternative construction the tablet may be formed in two parts each part being provided with a pointer and the two 25 parts being suitably connected together.

For office and/or household use the device may be of a conveniently large size, as shown in Figs. 20, 21 the pointers 9, 10 being preferably relatively adjustable in any 30 suitable manner and these latter may be mounted on an endless band 32 or other suitable carrying member mounted on rollers 33, 34 actuated by a pull member 35 or push device adapted to rotate the rollers 40 and a ratchet wheel 36 which may be maintained in any adjusted position by the action of a pawl 37 and spring 38.

In the application of the invention to a watch or clock, the device may be combined 45 therewith as a permanent fixture thereto as in Fig. 22 in which 39 is the watch, 40, 41 the hour and minute hands thereof and 9, 10 the pointers. These latter are mounted on the same spindle or arbor as the hands of 50 the watch and are independently movable thereof in any suitable manner. The two pointers 9 and 10 may have tubular bosses, one of which may be split to receive the actuating end of the other pointer so that one 55 pointer or both pointers can be pulled out so as to adjust the pointer or pointers in position the pointers after adjustment being movable simultaneously. The device may be provided as an indication on the 60 watch or clock or the said device may be provided in a circular form as an attachment to either a watch or clock or to both a watch and clock and may be removable from both when desired.

65 As applied to the dial of a clock of any

type the dial 42 or face thereof is provided with the numerals 1 to 31 and with four dots after the numeral 31, the numeral 1 preferably being placed or situated above or below the hour indication XII as shown 70 in Fig. 23. The numerical scale 3 is marked circular-wise around the dial 42 or face of the clock and may be indicated on a piece of paper, cardboard or the like, or may be stamped, painted or indicated thereon in 75 any convenient manner. Inside the numerical scale 3 is indicated the diurnal scale 4, the day of the week indicated adjacent the numeral 1 being preferably Sunday, so that in successive order the day of the week opposite the numeral 31 will be Tuesday, the dots after the numeral 31 having Wednesday, Thursday, Friday and Saturday adjacent thereto and as read from the numeral 31 in a clockwise direction. Inwardly of 80 the diurnal scale 4 and disposed to an equal extent on each side of the center is a sector 43' bearing the diurnal indications Thursday, Friday, Saturday, Sunday, Monday, Tuesday, and Wednesday corresponding 85 respectively to the last three dots before the numeral one and to the numerals 1, 2, 3 and 4 on the numerical scale. Suitably mounted at the center of the dial or face of the clock or watch are two pointers 9, 10, one 90 having a preferably crescent shaped outer end 43, hereinafter referred to as the numerical pointer, the other pointer being formed as an ordinary pointer and referred to hereinafter as the diurnal pointer 10. 100 The two pointers are relatively adjustable within the limits of the diurnal indications on the stationary sector 43' hereinbefore referred to, such adjustment being allowed for by a suitable formation of the bosses of the 105 two pointers. In one construction for adjustment the two pointers 9, 10 may be mounted on a tube 44, Fig. 24, the numerical pointer 9 being loose on the tube 44 and arranged outside the diurnal pointer 10 and 110 between the diurnal pointer 10 and a suitable head 45 on the outer end of the carrying tube 44 which may be provided with a cross pin 45' adapted to engage a V or other slot 46 in the boss of the numerical pointer. 115 The two pointers 9, 10 may be adjusted relatively by pressing on the head end 45 of the tube 44 against the action of a spring 46' and thereafter turning the said head 45, tube 44 and diurnal pointer 10 rigidly 120 mounted in the tube. On releasing the head end of the tube the spring forces the head end of the tube and the diurnal pointer forward and the tube is manipulated so that the cross pin therein engages in another recess in the boss of the numerical pointer 125 the two pointers being then movable simultaneously while still retaining their relative distance apart. The carrying tube 44 may be suitably mounted on the central 130

spindle of the dial or face of the clock or watch or may be carried on a suitable pin in a circular frame bearing the numerical and diurnal scales which frame may be sprung into position on the clock or watch, dial or face.

The device may be arranged in the position of the date indicator usually occupied on large eight day clocks or on watches 10 the single pointer therein used being placed by the two pointers hereinbefore described. In this construction the two pointers would be moved once simultaneously every twenty 15 four hours by the clock mechanism their relative adjustment being effected by hand once a month or as found necessary, such construction being shown in Figs. 29, 30 and 31. In Fig. 29, the clock mechanism frame is indicated at 61 the arbor 62 having a gear 20 wheel 63 with 35 teeth and driven by a suitable pinion from the clock mechanism. The pointer 10 may be adjusted each month by means of the slotted disk 64 tight on the center arbor and the rod 65 engaging the 25 slot 66 in the disk 64; or if so desired the rod 65 may be caused to act on the gear wheel 63 so as to effect the monthly adjustment.

The dial or face of the clock or watch 30 may also be provided with a circular ring bearing the months on its face, the ring being rotatable by a pull or push member so as to bring the proper month into position 35 behind a suitable opening in the dial or face of the clock or watch. If so desired the said ring may be operated by gearing from the main driving spindle of the clock or watch or in any other suitable manner.

In a further modification the numerical 40 and diurnal scales 3, 4, respectively may be mounted on separate disks 47, 48 as shown in Fig. 25. In this construction the disk bearing the numerical scale 3 is shown at 47 and the diurnal scale disk at 48. The 45 pointers 9, 10 being as before relatively adjustable so that one or other pointer can be shifted to the correct day of the week on the first day of the month or at other convenient time. After adjusting either pointer or 50 both pointers 9, 10 to their relatively correct position on the first day of the month so that the pointer indicates the correct day on which the first day of the month begins and the other pointer indicates the numeral 55 1, the two disks 47 and 48 are simultaneously rotated daily or when necessary or convenient by the fingers into a position such that the numeral indication of the day of the month and the diurnal indication 60 come into correct position with the respective pointers. The pointers 9, 10 thus retain throughout any one month the position to which they have been set at the beginning of the month consequently simultaneous movement of the disks 47, 48 is all

that is required to give the correct number of the day of the month and the day of the week throughout the remainder of the month after the first of the month. The construction permitting of the adjustment 70 of the pointers may be effected in a manner such as hereinbefore described or in any other suitable and convenient manner. The disks 47, 48 carrying the numerical and diurnal indications may be rotated simultaneously by a pull cord or by a push device or other suitable means. When two separate disks or separate rings are used they may be mounted on the same spindle and be interconnected in any suitable manner so as to 80 give the simultaneous movement.

Above the casing or frame 49 carrying or forming the support of the calendar a roller 50, bearing indications of the month may be arranged such roller being rotatable by hand 85 or from a projection or projections on the disk or ring or on the separate disks or rings.

In Figs. 26 and 27 the calendar is shown as comprising a frame 49 or casing within 90 which a disk 51 of cardboard wood or other suitable material is mounted on a pivot 52. As shown the disk 51 projects sidewise through slits in the frame so that the said disk can be rotated by the fingers; or the frame may be recessed and completely inclose the disk. In this construction the numerical and diurnal scales 3, 4 respectively are indicated on one and the same disk, the numerals of the numerical scale being visible only through an opening 53 in the front of the frame or casing and seven of the diurnal indications being visible through an opening 54 adjacent the opening 53. Outside of the frame or casing is a pointer 105

10 mounted on the pivot 52 carrying the disk, the said pointer being adjustable throughout a distance corresponding to the days of one week. In lieu of the centrally arranged pointer a slidible pointer may be mounted in a groove or recess 55 adjacent the diurnal indication opening 54. Near the bottom of the frame 49 is a roller 56 bearing the monthly indications or such roller may be replaced by two rollers 57, 58 110 bearing an endless band 59 having the monthly indications thereon. If so desired the roller or endless band may be replaced by a circular form of monthly indications as shown at 60, or by printed slab or slips 115 showing month and year.

As the date indicator may be constructed in many forms without departing from the nature of the invention I desire it to be understood that I do not limit myself to the 125 precise constructions hereinbefore described.

If desired an indicator having the signs 0, + or - may be employed and may take the place of the movable pointer and may be adapted to the vertical or circular form 130

of calendar. As before the diurnal indications throughout the month are indicated on the calendar the numeric indications being so arranged that the 1st, 8th, 15th, 22nd 5 and 29th are always opposite a Sunday. The indicator may be the form of an endless band on rollers revolved by a knob on which are printed the signs 1, 2, 3, 0 placed vertically or horizontally and the required 10 number indicated by a movable pointer which also bears a plus or minus indicator. This indicator is set once a month showing either +1, +2, +3 or -1, -2, -3 or a cipher 0. To set the indicator correctly at 15 the beginning of each month proceed as follows:—If the 1st (always marked Sunday) does in effect fall on Sunday, set the indicator to 0 which is equivalent to 2 pointers being in line, for the rest of the month the 20 days of the week would be as permanently indicated.

But should the 1st of the month though marked Sunday, not in effect fall on a Sunday, but on a Wednesday, the indicator 25 would then be set to +3, which is equivalent to the movable pointer hand being 3 divisions lower than the pointer. Should the 1st of the month be on a Friday it would be necessary to set the indicator to -2 30 which is equivalent to the movable pointer hand of the pointer date indicator hereinbefore described, being two divisions higher than the fixed pointer hand. Assume that a date indicator of this description had been 35 bought on the 19th of the month and that the first day of the month had already passed, all that is required is to ascertain what day of the week the 19th actually falls on. For example say it is found that the 40 19th is on Friday, the permanently marked numerals show the 19th to be Thursday *i. e.* one day in advance of Thursday. Therefore the indicator must be set to +1, which denotes that during the rest of the month 45 (as also the preceding days) one day must be added to the day that is marked *i. e.* the 6th would have been Saturday, the 28th will be Sunday, *i. e.* one day in advance of the day permanently indicated which is 50 Saturday.

The above modification may be applied to a watch above or on the dial of which is provided the indicator. If this indicator had been set to 0, the dial would read Monday the 2nd but as it is set to +2, it will be read as the 2nd Wednesday, *i. e.* 2 points ahead of the Monday permanently marked. This practically amounts to imagining another pointer hand which is not really there, 55 and is therefore merely a modification of the clock form of indicator hereinbefore described. The indicator may be in the form of a small ivory tablet pendant or fixed to the watch or the watch strap with the figures 1, 2, 3, 0 printed thereon and at the be-

ginning of each month (or whenever the indicator is first brought in use) to affix or mark above a plus or minus sign, and a dot or some other mark over the 0 when the 0 is to be indicated, the sign being erased 70 at the beginning of each month as required; or three thin tablets to slide into a groove and reversible may be used as indicators, no 0 sign being then necessary as a blank would be sufficient. 75

An indicator of this description could always be carried on the watch chain without a calendar, and provided it was set correctly at the beginning of the month would be always serviceable. For instance assume the 80 indicator to be set to +2 which means that the 1st of the month fell on a Tuesday. There may then be no need to refer to it at all. Then someone might ask what day of the week is the 24th. To ascertain this divide 24 by 7 which gives a remainder of 85 3; counting Sunday always as 1, 3 will be Tuesday, but the indicator says +2 so add two more days which makes Thursday. If the indicator had said 0 nothing would be 90 added, it would therefore be Tuesday. This indicator may be carried from a date indicator or a date indicating watch and is merely a modification of the pointer indicator hereinbefore described in which Sunday is always fixed as the 1st or rather the 1st as always Sunday. If the 1st is always Sunday and the numerical indication be divided by 7, the 1st day of the remainder will always be a Sunday. For example 95 100 what day of the week is the 17th. Now, 17 divided by 7 gives 2 and 3 over, the 2 may be discarded merely the remainder having to be considered. 3 days in advance of Sunday is Tuesday, *i. e.* the 17th is on Tuesday; 105 assuming the indicator is set at 0. But if it is set to 1 it would be Monday, and if set to 3 it would be Saturday. 3 however is the greatest divergence, because the 3 figures above and below added to the 0 or 110 Sunday make up the 7 days of the week.

The calendar with indicator may be applied to a pen holder having a numerical scale and a diurnal scale provided thereon, the principle being the same as my pointer 115 calendar but dispensing with the movable pointer hand by having a revolving or other suitable indicator at the top and a sliding indicator movable day by day. The slideable indicator may run up the middle of 120 the pen holder between the figures, and with the figures visible it is an easy matter to count three back or two or three forward as the case might be.

This construction of date indicator apart 125 from the penholder might equally well be used as a pendant for a watch chain.

What I claim is:—

1. A date indicator comprising a support having a longitudinal opening formed 130

therein, said support being provided near and upon opposite sides of the longitudinal opening with a numerical scale and a diurnal scale, a longitudinally movable element 5 operating within the longitudinal opening, and pointers carried by the longitudinally movable element, one pointer being adjustable longitudinally of the element with relation to the other pointer.

10 2. A date indicator comprising a support having a longitudinal opening formed therein, said support being provided near and upon opposite sides of the longitudinal opening with a numerical scale and a diurnal scale, a longitudinally movable element 15 arranged within said opening, a pointer carried by the element to coact with one scale, a second pointer slidably engaging said element and adapted to be adjusted longitudinally thereof, and means to move said element.

20 3. A date indicator comprising a support having a longitudinal opening formed therein, said support being provided near

and upon opposite sides thereof with a numerical scale and a diurnal scale, an element mounted within the longitudinal opening to be moved longitudinally thereof and having a longitudinal slot, a pointer fixed to the element and coöperating with one scale, 30 a second pointer slidably mounted within said slot and coöperating with the other scale, and means to move said element.

4. A date indicator comprising a support provided with independent and relatively 35 fixed non-adjustable numerical scale and diurnal scale in combination with pointers co-operating respectively with said scales and adapted for adjustment with relation to one another to initially register the respective 40 pointers with a particular number and a particular day, and provide for the maintenance of this adjusted relation of the pointers throughout a predetermined use of the date indicator.

45 In testimony whereof I have hereunto signed my name.

G. P. LELY.
